Joseph F. Donahue

BY

George J. Ottach

ATTORNEY.

UNITED STATES PATENT OFFICE.

JOSEPH F. DONAHUE, OF SOUTH BEND, INDIANA.

ROOFING.

Application filed December 23, 1921. Serial No. 524,511.

To all whom it may concern:

Be it known that I, JOSEPH F. DONAHUE, a citizen of the United States, residing at South Bend, in the county of St. Joseph and 5 State of Indiana, have invented certain new and useful Improvements in Roofing, of which the following is a specification.

The invention relates to roofing, and has for its object to provide a roofing formed 10 from a plurality of rectangular shaped flexible or pliable shingles, having their edges interlocked in slits of adjacent shingles, said slits at their inner ends terminating in angular disposed slits thereby forming members which will underlie the adjacent shingles and support the same in such a manner that the inner edges formed by the slits will be in vertical alignment and the members formed by the slits will support the 15 shingles in a close joint, and in such a manner that upon pressure on the joints, acute bends will be prevented from being formed in the shingles, thereby obviating breaking or fracturing of the shingles.

20 A further object is to provide a roofing shingle formed from a plurality of rectangular shaped pliable shingles, said shingles having two of their converging sides provided with aligned slits, the inner ends of 25 which terminate in slits at substantially right angles to the converging sides, thereby allowing portions of the shingles to be offset when the shingles are interengaged.

30 A further object is to provide a pliable shingle substantially square in shape, said shingle having extending inwardly from converging sides thereof aligned slits at substantially forty-five degrees to the converging sides and terminating in outwardly extending slits at substantially ninety degrees to the sides, said slits allowing the formation 35 of close joints when the shingles are interengaged and in such a manner as to support the shingles against acute bending 40 under pressure as distinguished from joints formed from enlarged recesses.

45 With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit 50 of the invention.

In the drawing:—

Figure 1 is a top plan view of a portion of a roof formed from interengaged shingles.

Figure 2 is a detail perspective view of adjacent shingles, showing the interengagement thereof.

Figure 3 is a detail perspective view of the slit corner of a shingle, showing a portion of an adjacent shingle interengaged therewith.

Figure 4 is a detail sectional view taken on line 4—4 of Figure 3.

Referring to the drawing, the numeral 1 designates a portion of a roof formed from a plurality of rectangular shaped pliable or 70 flexible shingles 2. The shingles 2 are preferably square, however, it is to be understood that they may be varied in shape and also in material. The shingles 2 adjacent one of their corners 3 are provided with inwardly 75 extending aligned slits 4 which extend inwardly at about forty-five degrees to the converging sides 5 of the shingles 2. The inner ends 6 of the slits 4 merge into outwardly extending portions 7 preferably at 80 about ninety degrees to the sides 5 and at substantially a registering angle with the edge 5 of the adjacent shingles, thereby allowing the portion 8 formed by the slits 4 and 7 to be downwardly offset when the 85 adjacent shingle is received. By so forming the shingles, that is with slits 4 and 7, a more tight, close and water proof joint is provided than is possible where slots are used, as distinguished from slits.

By referring to Figure 4, it will be seen that the walls 9 and 10 formed by the slit 4 will be substantially in the same plane and that when pressure is applied on the roofing, for

instance by walking over the same, the portion of the adjacent shingle 2 will not be acutely bent or bent at all at the point 11, which would be the case, and is the case where enlarged recesses are used, as distinguished from slits, hence the life of the 100

roofing is prolonged, and a closer joint is provided, thereby rendering the joint more water proof. It will also be seen that by providing the slits as distinguished from 105

enlarged recesses, that during the course of manufacture, that a simple die may be employed, and one which is easily kept sharp.

This is not the case where enlarged recesses are used, as a die is necessary, which is relatively small with parallel cutting edges and 110

an angled cutting edge connecting the two, which form is more or less trouble to keep in sharpened condition and is expensive to make. The corners 3 have their points cut 5 away as at 3^a, thereby eliminating the exposed portions of the corners 3 which may easily curl.

From the above it will be seen that a roofing shingle is provided, which is simple in 10 construction and one which may be easily manufactured and one wherein the dies for forming the slits are simple in construction, as distinguished from dies necessary for cutting slots. It is obvious that the slits or cuts 15 may be formed by relatively narrow slots, however when the shingles are interengaged the cuts become relatively narrow slots.

The invention having been set forth what is claimed as new and useful is:—

20 1. A roofing formed from a plurality of rectangularly shaped shingles having their corners disposed in alignment transversely and longitudinally of the roof, said shingles having one of their corners provided with 25 slits extending inwardly from the converging sides of the corner and merging into slits extending outwardly towards the converging sides of the corner.

2. A roofing formed from a plurality of 30 shingles, said shingles being provided with corners, the sides of which are at substantially a right angle to each other, one of said corners being provided with inwardly 35 extending slits for the reception of the sides of adjacent shingles, said slits merging into outwardly extending slits, thereby forming a portion of the shingle adapted to be offset from the shingle when the adjacent sides of adjacent shingles are received in the slits.

3. A roofing formed from a plurality of 40 rectangularly shaped shingles having their corners disposed in alignment transversely and longitudinally of the roof, the sides of adjacent shingles being received in aligned slits extending inwardly from the converging 45 sides adjacent one corner of the shingles, said aligned slits being disposed at substantially forty-five degrees to the converging sides and merging into outwardly extending slits at substantially ninety degrees to the 50 converging sides.

4. A shingle formed from pliable material and substantially square in shape, said shingle adjacent one of its corners being provided with inwardly extending aligned slits 55 disposed at substantially forty-five degrees to the converging edges including the corner and merging into outwardly extending slits at substantially ninety degrees to said converging edges.

5. A shingle formed from pliable material and substantially rectangularly shaped, said shingle adjacent one of its corners being provided with inwardly extending slits merging into outwardly extending slits.

6. A shingle formed from pliable material and angularly shaped, said shingle adjacent one of its corners being provided with inwardly extending straight slits, said straight slits merging into outwardly extending straight slits.

7. A shingle formed from pliable material, said shingle being provided with inwardly extending slits, said slits merging into slits extending in a direction out of alignment with the first mentioned slits.

In testimony whereof I affix my signature.
JOSEPH F. DONAHUE.
